(57) **CLAIM**

The ornamental design for an adjustable clamp, as shown and described.

DESCRIPTION

FIG. 1 is a front side perspective view of an adjustable clamp according to my new design with the jaws of the adjustable clamp shown in a retracted and closed position;

FIG. 2 is a front elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear elevation view thereof;

FIG. 8 is a front side perspective view of the adjustable clamp with the jaws of the adjustable clamp shown in an extended and closed position;

FIG. 9 is a front elevation view thereof;

FIG. 10 is a left side elevation view thereof;

FIG. 11 is a right side elevation view thereof;

FIG. 12 is a top plan view thereof;

FIG. 13 is a bottom plan view thereof;

FIG. 14 is a rear elevation view thereof;

FIG. 15 is a front side perspective view of the adjustable clamp with the jaws of the adjustable clamp shown in a retracted and open position;

FIG. 16 is a front elevation view thereof;

FIG. 17 is a left side elevation view thereof;

FIG. 18 is a right side elevation view thereof;

FIG. 19 is a top plan view thereof;

FIG. 20 is a bottom plan view thereof; and,

FIG. 21 is a rear elevation view thereof.

The broken lines in the drawings depict portions of the adjustable clamp that form no part of the claimed design.

1 Claim, 15 Drawing Sheets
